US0D1059022S

(12) **United States Design Patent** (10) **Patent No.:** **US D1,059,022 S**
(45) **Date of Patent:** **** Jan. 28, 2025**

(54) **BASE FOR STORAGE BOX**

(71) Applicant: **L&F PLASTICS, CO., LTD.**, Miaoli County (TW)

(72) Inventor: **Mu-Chuan Hsu**, Miaoli County (TW)

(73) Assignee: **L&F Plastics, Co., Ltd.**, Miaoli County (TW)

(**) Term: **15 Years**

(21) Appl. No.: **29/872,054**

(22) Filed: **Mar. 6, 2023**

(30) **Foreign Application Priority Data**

Sep. 12, 2022 (TW) 111304523

(57) **CLAIM**

The ornamental design for a base for storage box as shown and described.

DESCRIPTION

FIG. 1 is a top front perspective view of a base for storage box showing my new design;

FIG. 2 is a front view thereof;

FIG. 3 is a rear view thereof;

FIG. 4 is a right side view thereof and the left side view being a mirror image;

FIG. 5 is a top view thereof;

FIG. 6 is a bottom view thereof; and,

FIG. 7 is a bottom rear perspective view thereof.

The dashed broken lines in the figures show portions of the base for storage box that form no part of the claimed design.

1 Claim, 6 Drawing Sheets
